UNITED STATES PATENT OFFICE.

ADOLPH O. NELSON, OF CHICAGO, ILLINOIS.

DESIGN FOR A HOLDER FOR TOILET ARTICLES.

Application filed November 14, 1925. Serial No. 15,420. Term of patent 3½ years.

To all whom it may concern:

Be it known that I, ADOLPH O. NELSON, a citizen of the United States, residing at Chicago, in the county of Cook and State of Illinois, have invented a new, original, and ornamental Design for Holder for Toilet Articles, of which the following is a specification, reference being had to the accompanying drawing, forming part thereof.

I claim:

The ornamental design for a holder for toilet articles, as shown.

ADOLPH O. NELSON.
